(57) **CLAIM**

The ornamental design for a coupler for actuator, as shown
and described.

DESCRIPTION

FIG. 1 is a top perspective view of a coupler for actuator
showing my new design;

FIG. 2 is a bottom perspective view thereof;

FIG. 3 is a front view thereof;

FIG. 4 is a rear view thereof;

FIG. 5 is a right side view thereof; the left side view is a
mirror image of the right side view thereof;

FIG. 6 is a top plan view; and,

FIG. 7 is a bottom plan view thereof.

The broken lines in the drawings are for the purpose of
illustrating unclaimed portions of the coupler for actuator
and form no part of the claimed design.
